UNITED STATES PATENT OFFICE.

CARL HOLMSTRÖM, OF GLASGOW, SCOTLAND.

BREECH BLOCK AND CHAMBER FOR ORDNANCE.

SPECIFICATION forming part of Letters Patent No. 705,841, dated July 29, 1902.

Application filed January 3, 1902. Serial No. 88,367. (No model.)

To all whom it may concern:

Be it known that I, CARL HOLMSTRÖM, engineer, a subject of the King of Sweden and Norway, residing at Parkhead Forge Rolling Mills and Steel Works, Glasgow, Scotland, have invented certain new and useful Improvements Relating to Breech-Loading Ordnance, of which the following is a specification.

10 This invention relates to breech-loading ordnance and has special reference to the formation of the breech-block and its chamber.

The chief object sought in the construction of the screw-threaded breech-blocks of ordnance is the shortest length compatible with security in closing the breech, so that the block shall be comparatively light in weight and capable of easy manipulation in a small space in opening and closing the breech.

20 The length of the block must in all cases be such that the screw-threads will have sufficient surface area to resist the pressure in the gun. It is of great importance that the threads should be so formed that a slight an-

25 gular displacement or incomplete closing of the block will not seriously impair the extent of the area of the threads in contact with each other, so that the block will have a satisfactory bearing-surface throughout its en-

30 tire length and will not lie loosely in the chamber, so as to offer through its threads insufficient resistance to the pressure arising on discharge of the gun to insure a safe locking. It is, furthermore, of importance that

35 the block shall require only a comparatively small angular movement in being locked and unlocked.

Many attempts have been made to construct a breech-block which shall effectually fulfil

40 the above requirements. Probably the best known form of block for such purpose is that in which the periphery is made in steps and with one or more gaps, the curved surface of each step being threaded. There are, how-

45 ever, difficulties in connection with stepped blocks of this description. For instance, the threads cannot be made continuous from one step to another by reason of the abruptness of the radial divisions between the contiguous steps. Therefore in forming the said threads on the blocks the thread-cutting tool has to pass suddenly from one surface to an-

other and cannot be relied upon for the accurate formation of the threads all around the block. Moreover, as the threads cannot 55 be made continuous, but are obliged to be in a series of interrupted sections, there is a loss of bearing-surface due to the interruptions of the threads. It has also been proposed to have the periphery of the block of 60 volute or spiral formation; but although in such case the screw-threads could be made continuous the locking of the block in the breech-chamber would be most unsatisfactory, owing to the great diminution of the re- 65 sisting-surface of the threads if the block failed in the slightest degree to perform its full angular movement in the locking operation. Such a block would be impracticable for use in ordnance because of its liability to 70 be blown out from the breech of the gun.

Now according to my invention I overcome all the above-stated objections by so constructing the block in cross-section that its contour or periphery presents a series of arcs 75 of concentric circles described about the axis of the block, the successive arcs being joined by straight or curved surfaces, which, with the exception of the first and last, are so arranged as to avoid abrupt transition from one 80 to another of the circular arcs. Thus notwithstanding the fact that the periphery of the block has a series or two or more series of curved surfaces at different distances from the axis the threads can be made continuous 85 throughout each entire series of such surfaces, except, of course, at the part where the gap or gaps are formed. The breech-chamber of the gun is similarly formed to receive the said block.

In order that my said invention may be clearly understood and readily carried into effect, I will describe the same more fully, with reference to the accompanying drawings, in which—

Figures 1 and 2 are cross-sections of my improved block and breech-chamber, the former figure representing the block locked and the latter unlocked. Fig. 3 is a development of the peripheral surface of this block. Figs. 100 4 and 5 are cross-sections of a modified form of my block and breech-chamber, the former figure representing the block locked and the latter unlocked. Fig. 6 is a development of

the peripheral surface of this form of the block. Figs. 7 and 8 are cross-sections of a further-modified form of my block and breech-chamber, the former figure representing the 5 block locked and the latter unlocked. Fig. 9 is a development of the peripheral surface of this form of the block.

In all the figures, A is the block, and B the breech end, of the gun.

On reference to the various figures it will be seen that the arcs $a' a^2 a^3$, &c., are not interrupted by radial surfaces, as has hitherto been the case with stepped blocks, my object being to avoid any abrupt or sudden separation of one arc from another except at the gap or gaps a , where there are no screw-threaded surfaces.

In Figs. 1, 2, and 3 the arcs $a' a^2 a^3$, &c., (all of which are described from the point x .) are connected by straight surfaces a^4 , that are tangential to the arcs of smaller radius and are joined to the arcs of larger radius by curves a^5 .

In Figs. 4, 5, and 6 the concentric arcs $a' a^2 a^3$, &c., are connected by sloping or inclined surfaces a^6 , which are curved where they meet said arcs.

In Figs. 7, 8, and 9 the said concentric arcs $a' a^2 a^3$ are connected by curves a^7 , of ogée formation, without any straight surfaces.

With the above-described forms of the block it is practicable for the entire surface of the arcs $a' a^2 a^3$ and their connecting portions to be made with uninterrupted threads. I am thus able to provide the series of arcs with continuous locking for supporting the block in the breech-chamber against the endwise thrust or pressure, and consequently my improved block can be made appreciably shorter than the ordinary stepped blocks hitherto constructed.

It will be apparent that the periphery of my said block has no spiral or volute surfaces, but consists almost entirely of a series of concentric surfaces, so that a slight angular displacement of the block would not have the effect of dangerously reducing the area of the bearing-surface of the threads in contact, as would be the case with a block of the volute or spiral formation hereinbefore alluded to.

I do not wish to confine myself to any par-

ticular degree of inclination or curvature of the surfaces joining the concentric arcs of my block so long as their abruptness is not such as to render the continuation of the 55 threads upon them impracticable. Likewise I do not wish the formation of my block to be confined to any specific number of threaded segments and gaps, as of course their number will somewhat depend upon the dimensions 60 of the block. In Figs. 1 to 6 I have shown one gap and five threaded segments and in Figs. 7 to 9 two gaps and six threaded segments. In the latter case the threaded segments are located symmetrically around the 65 block. I also wish it to be understood that my block can be mounted in any appropriate kind of swinging carrier and can be actuated by any suitable kind of breech mechanism.

What I claim, and desire to secure by Letters Patent of the United States, is—

1. A breech-block which in cross-section comprises a series of concentric steps of different radii joined by surfaces other than radial with respect to the axis of the block so 75 that the locking-surfaces can all be formed with continuous or uninterrupted screw-threads for the purpose specified.

2. A breech-block which in cross-section comprises a series of concentric steps of different radii joined by inclined surfaces substantially as and for the purpose specified.

3. A breech-block which in cross-section comprises a series of concentric steps of different radii joined by inclined surfaces that 85 are approximately tangential to the concentric surfaces of larger radius and curved where they meet the concentric surfaces of smaller radius substantially as and for the purpose specified.

4. A breech-block which in cross-section comprises a series of concentric steps of different radii joined by curved surfaces of ogée formation substantially as and for the purpose specified.

In testimony whereof I have hereunto set my hand, in presence of two subscribing witnesses, this 28th day of November, 1901.

CARL HOLMSTRÖM.
